Primary Examiner — Richard A Edgar*Assistant Examiner* — Audris Park(74) Attorney, Agent, or Firm — Nitin Kaushik(57) CLAIM

I claim the ornamental design for a floor lamp with end table, as shown and described.

DESCRIPTION

FIG. 1 is a Perspective view of a floor lamp with end table showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof; and,

FIG. 7 is a Bottom view thereof.

The broken lines in the drawings depict portions of the floor lamp with end table that form no part of the claimed design.

1 Claim, 5 Drawing Sheets(56)
